SELF-ARMING PROJECTILE

Fred Perlin, Edgerton, Wis., assignor to The Parker Pen Company, Janesville, Wis., a corporation of Wisconsin

Application December 8, 1951, Serial No. 260,678

3 Claims. (Cl. 102—38)

The present invention relates to self-arming, explosive projectiles and particularly to a self-arming projectile especially well-adapted for use in connection with small arms.

The projectile is of such character as to be adaptable primarily to fixed charge cartridges, and although the projectile is intended particularly for use with small arms, its construction enables its adaptation to weapons of any caliber utilizing fixed charge cartridges.

An object of the invention is to provide a self-arming, explosive projectile adapted for use in a cartridge having a case of common construction such as used in heretofore well-known cartridges, which projectile has a smooth and substantially unbroken outer surface.

A still further object is the provision of a cartridge including a self-arming, explosive projectile that is positively disarmed.

Another object is the provision of a cartridge including a self-arming, explosive projectile having no exposed parts other than the casing of the projectile, in which the projectile is not likely to be damaged in the handling of the cartridge preparatory to firing.

Still another object is the provision of a self-arming, explosive projectile having substantially no change in shape as compared with a common solid bullet.

A further object is the provision of a self-arming, explosive projectile of novel construction for use primarily in connection with small arms, which is of such character as to enable it to be used as a spotting round or as an explosive round.

Another object is to provide an explosive projectile of novel construction for use in a fixed charge cartridge which is put in disarmed condition in the manufacture of the cartridge and remains so disarmed by means of the cartridge case in engaging the projectile, and which is automatically armed upon its leaving the cartridge case and the barrel of the weapon from which it is fired.

Another object is the provision of a novel projectile of the foregoing character that is initially disarmed and remains disarmed until fired, whereupon it immediately becomes armed, eliminating the necessity for manual manipulation for the purpose of arming the projectile preparatory to firing it.

A further object is the provision of a self-arming projectile having an inertia-actuated priming or detonating element in which, when the projectile is in disarmed condition, the detonating element is positively locked against relative movement such as to cause detonation of the charge in the projectile.

Still another object of the invention is the provision of a projectile for use in a fixed charge cartridge, having an inertia-actuated detonating element contained entirely within the interior of the projectile, and means for positively locking the detonating element in disarmed position, in which the locking means is maintained in effective position by the cartridge case.

Another object is the provision of a projectile having an ignitable charge therein, for use in a cartridge having

2

an ignitable propelling charge, in which the interior of the projectile is sealed from the interior of the cartridge case for preventing propagation of ignition from the propellant in the cartridge case to the charge in the projectile.

A further object is to provide a self-arming projectile of simple and inexpensive construction.

Further objects will appear upon reference to the following detailed description taken in conjunction with the accompanying drawing, in which:

Figure 1 is a fragmentary longitudinal sectional view of the projectile and forward portion of the cartridge case with which it is used; and

Fig. 2 is an enlarged transverse sectional view taken on line 2—2 of Fig. 1.

The projectile and cartridge case illustrated in the drawing together form a fixed round or cartridge. The projectile is shown as a whole at 10 and the cartridge case at 12. The cartridge case 12 may be of any suitable known form and construction and includes a rear tubular portion 14 containing an ignitable propelling charge 16 which may be of any suitable material effective for propelling the projectile from the weapon in which the ammunition is used. The cartridge case 12, as is usual, includes a percussion cap (not shown) at the rear for igniting the propelling charge. The forward end of the cartridge case 12 is of reduced diameter as indicated at 18 for engaging and gripping the projectile 10 and surrounding the rearward portion thereof as is customary in fixed charge cartridges. The cartridge case is of common construction such as used in heretofore well-known cartridges and need have no special features of construction made necessary by reason of its cooperation of the projectile of the present invention.

In a fixed charge cartridge the propelling charge is placed in the manufacture of the cartridge and it cannot thereafter be altered, the case of the cartridge being securely fitted on the projectile as by means of a press fitting operation or other desired operation effective for retaining the case and projectile in assembled condition and preventing removal of the projectile from the case except when the cartridge is fired.

The projectile 10 as illustrated is in disarmed condition, it being so maintained by the cartridge case. The projectile includes a shell or casing 20 made up of an outer jacket member 22 and an inner, liner member 24 shaped complementally to the outer element throughout the greater part of its area. The liner member preferably is formed from steel but other material may be used. The jacket member 22 may be formed of any suitable metal and has a smooth outer surface (except for small apertures to be referred to later), including a tapered forward end 26 terminating in a rounded small dimension nose 28. The overall shape of the projectile and its smooth outer surface as determined by the jacket member 22 are effective for minimizing air resistance. The liner member 24 terminates forwardly in a flattened end 30 which is accordingly spaced rearwardly from the nose 28 of the outer jacket member 22. The flattened portion 30 is provided with an aperture for receiving a screw or pin 32 having a roughened or threaded portion 48, as will be referred to later, and having a head 34 for engaging the outer surface of the flattened portion 30 for establishing a reaction point for the screw in the function of the latter in securing certain elements of the projectile together. The screw 32 extends longitudinally through the projectile and its rear threaded end 36 is threaded into a complementary threaded aperture in a closure plate or backing member 38 which closes the rear end of the casing or hollow member 20. The plate or backing member 38 may have a reduced diameter portion 40 for extending into the liner 24 and a flange 42

for engaging the end edge of the liner 24, the flange preferably being of a diameter equal to the outer diameter of the inner element 24 so that it fits within the jacket member 22, the latter being extended rearwardly an appropriate distance for accomplishing that purpose. The plate or backing member 38 may be press fitted in the liner 24 or sweated or otherwise fitted therein so as to seal the interior of the projectile against the propagation of ignition thereinto from the propelling charge in the cartridge case 12. The screw 32 on being tightened down into the plate or backing member 38 secures the backing member to the liner member 24 in an effectively integral arrangement. The jacket member 22 may be secured against easy removal from the liner 24 in an appropriate manner such as providing relative dimensions of the two elements for retaining them together by friction.

The projectile of the present invention may be utilized in connection with spotting operations, in which case it is so constructed as to provide a flare for visually indicating the target location of the projectile upon impact. When the projectile is intended to be used for such purposes, it is provided with an ignitable charge and provision is accordingly made for producing ignition in the projectile upon impact with the target. The particular means for producing such ignition will be referred to later.

When the projectile is to be used in spotting operations, a charge 44 that is capable of being ignited is employed. Any well-known material effective for producing a bright flare or other visible signal may be employed. Such materials are well known to those skilled in the art and it is believed unnecessary to specify particular materials. The charge 44 is placed adjacent the forward end of the projectile, and rearwardly thereof is a priming, igniting or detonating charge 46 capable of being ignited by a spark and propagating the ignition to the spotting charge 44. The charge 46 is loosely packed and capable of being compacted into a relatively small volume, for enabling the desired movement of the inertia-actuated detonating member as will be described later.

When the projectile is to be used as an explosive missile, the charge 44 is of high explosive character, and an ignitable detonating charge is employed of such character as to cause detonation of the explosive charge in response to ignition of the detonation. Accordingly, the charge 44 will be referred to as an explosive charge. The term "explosive" as used herein will be understood to include explosives in the broad general sense and includes not only high explosives but also low explosives and burning compositions suitable for spotting charges, as for example black powder and known incendiary materials. Similarly, "detonation" will be understood to include detonation of the character associated with high explosives as well as the action of producing ignition of burning compositions such as those mentioned.

The screw 32 is provided with a threaded, serrated or otherwise roughened portion 48 for aiding in producing an ignition spark. The threaded portion 48 preferably is provided with relatively sharp outer edges for the purpose of readily producing the spark intended. The roughened portion is of course preferably disposed adjacent the priming or detonating charge 46, and in the specific illustration is immediately embodied in that charge. This roughened portion is also spaced forwardly from the rear end of the projectile to insure against possible accidental ignition of the charge 46 when the projectile is in disarmed condition, as will be apparent as the description proceeds.

The projectile is designed for producing an ignition spark upon impact with the target, the spark being caused by an inertia-actuated element which in the specific illustration takes the form of a drive member 50 provided with a flint type pyrophoric element 52 capable of producing a spark when rubbed by or on a rough surface. The drive member 50 may be made of any desired material having substantial mass and has an overall cylindrical shape of relatively short axial dimension and provided

with a central aperture 54 for receiving the screw 32. The drive member is arranged for movement longitudinally of the projectile when the projectile is in armed condition, but has a disarmed position adjacent the rear end of the projectile, such disarmed position being illustrated in the drawing. For the purpose of mounting the pyrophoric element 52, the forward face of the drive member 50 is provided with an annular recess 56 in which the pyrophoric element is mounted, the latter being molded in the recess in an appropriate operation. The pyrophoric element also is provided with a central aperture for receiving the screw 32 and thus surrounds the screw.

In the disarmed position of the drive member 50 as shown in the drawing, the element 52 is disposed rearwardly of the roughened portion 48, but is arranged for engaging and rubbing on the latter upon relative forward movement in the projectile when so moved by inertia upon sudden deceleration of the projectile as in impact with the target. The charge 46 being loosely packed, as above mentioned, enables it to be compacted into a relatively small volume for enabling relative forward movement of the drive member in the projectile, whereby the element 52 engages and rubs on the roughened portion 48 and causes a spark for igniting the charge 46.

The drive member 50 is positively locked in its disarmed condition by means of a pair of pins 58 which in turn are maintained in locking position by the portion 18 of the cartridge case. These pins 58 which may consist of two or more in number fit rather loosely in and extend through apertures 60 in the two members 22 and 24 of the projectile casing 20. These apertures, as will be noted, are disposed adjacent the rear end of the projectile, so that when the drive member 50 is in its disarmed position the latter overlies the apertures. The pins are of appropriate length to extend inwardly beyond the element 24 and into engagement with the drive member. The drive member is provided with means such as a peripheral groove 62, or socket if desired, for receiving the inner ends of the pins. Such a peripheral groove is advantageous as compared with individual sockets, since when a peripheral groove is utilized the drive member need not be set in any predetermined angular position for receiving the pins.

The projectile is mounted in the cartridge case 12 in such position that the rear end portion of the projectile is received in and surrounded by the reduced portion 18 of the case 12 wherein the portion 18 covers the apertures 60 and the pins 58 and retains the latter in the apertures. The pins being of appropriate length to extend into the groove 62 positively lock the drive member 50 in its disarmed position so that as long as the projectile remains mounted in the cartridge case, as it will be at all times before firing, the possibility of accidentally exploding the charge in the projectile is eliminated.

Since the pins 58 fit loosely in the apertures 60 and groove 62 they are readily removable therefrom in response to centrifugal force of the projectile due to its rotation by the rifling of the weapon from which it is fired. Thus, upon firing of the cartridge and the projectile leaving the cartridge case, the pins 58 are thrown outwardly and the drive member 50 is enabled to move relatively forwardly in the projectile upon deceleration of the projectile on impact with the target. As explained above, such relative forward movement of the drive member causes rubbing of the pyrophoric element 52 on the threaded or roughened surface 48 producing a spark and igniting the charge 46 which in turn sets off the charge 44. It is of course desirable that the pins 58 are not thrown out of their apertures until the projectile leaves the barrel of the weapon from which it is fired. It will be readily understood that the length of the pins may be such as to prevent such action. The portion 18 of the shell case is brought into such tight fitting engagement with the projectile as to prevent propagation or transmission of igni-

tion from the interior of the cartridge case through the apertures 60 into the interior of the projectile.

The outer surface of the projectile is substantially smooth, being broken only by the very small aperture 60 whereby air resistance from this source is negligible.

I claim:

1. A self-arming projectile for use with a cartridge case containing a propelling charge and having an open forward end, said projectile including a casing having an imperforate forward end and containing an ignitable spotting charge and an igniting charge therein, the projectile having an opening in its side wall adjacent its rear end and being adapted for mounting of its rear end portion in the open end of a cartridge case in such position that the cartridge case covers said opening, an inertia-actuated drive member mounted for longitudinal movement in the casing and having a disarmed position adjacent the rear end thereof in overlying relation to said opening, said drive member including a flint type pyrophoric element and having a central aperture, locking means mounted in said opening projecting into engagement with said drive member for locking the drive member in its disarmed position, said locking means being positioned for retention in said opening by a cartridge case when the projectile is mounted therein and being readily removable outwardly from the opening upon the removal of the projectile from the cartridge case, and a central stem in the projectile casing with its forward end entirely within the casing and its rear end extending through the aperture in said drive member and having a roughened friction surface positioned for cooperation with said pyrophoric element for igniting said igniting charge in response to relative forward movement of the drive member.

2. A cartridge having a self-arming projectile, comprising a cartridge case containing a propelling charge and having an open forward end, said projectile including a hollow casing containing an ignitable charge and having an imperforate forward end and an open rear end, said casing having a side opening adjacent its rear end, the projectile having its rear end portion mounted in the open end of the cartridge case in such position that the cartridge case covers said side opening, a plate closing the open rear end of said hollow casing, a longitudinal member in the projectile casing with its forward end connected to the casing within and adjacent the forward end of the casing and to said plate for securing the plate to the casing, said longitudinal member having a roughened surface portion, a drive member in the casing movable longitudinally therein with a central opening receiving said longitudinal member and having a pyrophoric element engageable with said roughened surface, said drive member having a disarmed position adjacent the rear end of the casing wherein said pyrophoric element is disposed rearwardly of said roughened surface and the drive member overlies said side

opening, and locking means mounted in said side opening extending into engagement with said drive member for locking the drive member in its disarmed position, said locking means being retained in said side opening by the cartridge case when the projectile is mounted therein and being readily removable therefrom upon removal of the projectile from the cartridge case.

3. A cartridge having a self-arming projectile, comprising a cartridge case containing a propelling charge and having an open forward end, said projectile including a hollow casing made up of an outer jacket element and an inner complementally shaped element telescoped together and together having an open rear end, a plate closing said open rear end, said hollow casing having radially disposed apertures in its rear end portion, the projectile having its rear end portion mounted in the open end of the cartridge case in such position that the cartridge case covers said apertures, said projectile casing containing an explosive charge in its forward portion and a detonating charge rearwardly of the explosive charge, and having a tapered forward end, and the inner element of the casing having a flattened forward end spaced from the forward end of the outer element, a longitudinal member connected to the forward end of said inner element and said plate for securing the plate to the hollow casing and having a roughened surface adjacent said detonating charge, a drive member mounted in said casing for movement longitudinally therein with a central opening receiving said longitudinal member and having a flint type pyrophoric element surrounding the longitudinal member adapted to engage and rub on said roughened surface in response to relative forward movement of the drive member, said drive member having a disarmed position adjacent the rear end of the casing overlying said apertures and with said pyrophoric element rearwardly of said roughened surface, and locking pins mounted in said apertures extending into engagement with said drive member for locking the drive member in its disarmed position, said pins being retained in the apertures by said cartridge case and being freely removable therefrom by centrifugal force upon rotation of the projectile after its removal from the cartridge case.
